BUILDING OR SIMILAR ARTICLE

Frank P. Amie, Jr., 13 Grampian Road,
Liverpool, N.Y. 13088

Filed May 12, 1971, Ser. No. 142,844

Term of patent 14 years

Int. Cl. D25—03

U.S. Cl. D13—1

FIG. 1

FIG. 2

FIG. 3

FIG. 4

FIG. 1 is a plan view of the building or similar article;
FIG. 2 is a side elevational view thereof;

FIG. 3 is a fragmentary side elevational view taken at an angle of 36° from FIG. 2; and

FIG. 4 is a sectional view taken on the line 4—4 of FIG. 1.

The dotted line showing of the steps in the drawing is for illustrative purposes only and form no part of the claimed design.

I claim:

The ornamental design for a building or similar article, substantially as shown and described.
